UNITED STATES PATENT OFFICE.

NELSON E. SPRINGSTEEN, OF ROYAL OAK, MICHIGAN.

TICKET-PRINTING DEVICE.

991,660.

Specification of Letters Patent.

Patented May 9, 1911.

Application filed April 7, 1910. Serial No. 553,960.

To all whom it may concern:

Be it known that I, NELSON E. SPRINGSTEEN, a citizen of the United States of America, residing at Royal Oak, in the county of Wayne and State of Michigan, have invented certain new and useful Improvements in Ticket-Printing Devices, of which the following is a specification, reference being had therein to the accompanying drawings.

This invention relates to a device for printing tickets or similar slips upon a strip of material and delivering the same in a convenient manner to be torn off one or more at a time and the object of the invention is to provide certain new and useful features in the construction all as hereinafter described reference being had to the accompanying drawings, in which,

20 Figure 1 is a side elevation of a device embodying the invention; Fig. 2, a plan view of the printing end of the machine with the cover removed; Fig. 3, a longitudinal vertical section of Fig. 2.

25 As shown in the drawings 1 is a suitable cast metal base provided at one end with ears 2 between which arms 3 are pivoted to turn freely. The upper ends of these arms carry a shaft 4 upon which is mounted to 30 turn freely a roll of paper 5 of the desired width for the tickets. The arms 3 being pivotally attached to the base, the roll is simply held thereby in an upright position and rests upon the base 1, its own weight creating a 35 frictional resistance to the turning of the roll when the strip is fed forward through the printing device.

The end of the strip of paper is led from the roll through a suitably covered passage 40 6 to the printing roll 7 which is mounted in a casing 8 upon the forward end of the base. The shaft 9 of the roll 7 is mounted in bearings 43 in the sides of the casing and at one 45 end is provided with a knurled head or knob 10 outside of the casing by means of which the roll may be turned to feed the strip of paper forward. The roll is provided upon its face with a suitable printing die or type 50 11 and below said roll is a friction roll 12 to engage the underside of the strip of paper and press the same against the die of the printing roll. The shaft 13 of the friction roll extends through slots 14 in the sides of 55 the casing, said slots extending upward toward the axis of the printing roll.

An inking roll 15 having a facing 16 of

felt or other suitable material to hold the ink is mounted at the rear side of the printing roll to engage the type thereon and ink the same. The shaft 17 of the inking roll is 60 mounted in slots in the sides of the casing, said slots being open at the rear end so that the inking roll may be readily taken out, notches 18 being provided at the rear ends of the open slots 19 to receive said shaft and 65 hold the roll out of contact with the printing roll. Coiled springs are attached at one end to the outer ends of the shaft 17 and at their opposite ends to the shaft 13 outside of the casing and exert a force to draw said 70 shafts toward each other. As these shafts are mounted in slots which extend radially toward the axis of the printing roll said shafts will be moved in said slots by the springs radially toward the printing roll 75 and yieldingly hold the friction roll and the inking roll in contact with the printing roll. In the construction shown in Figs. 1, 2, and 3 the inking roll may be inked in any desired manner as by applying ink thereto 80 with a brush and to make the roll more accessible for applying the ink and so that it may be readily turned, it may be moved rearwardly against the action of the springs 20 to engage its shaft 17 with the notches 18 85 where the roll will be held by said notches out of contact with the printing roll and from beneath the casing top or cover 21 which has a pin 22 engaging an opening in a cross bar 23 of the casing and is detachably 90 secured to the casing at its forward side by a lock 24.

A suitable guide 25 for the strip of paper extends forwardly from the printing and friction rolls to an opening in the front side 95 of the casing and extending outwardly from the casing side is a suitable open guide frame 26 having slots in its edges to receive the edges of the strip and guide the same. The frame is open at its under side through its 100 outer end and is also open at its upper side except for a cross bar 27 which unites the side members of the frame at its outer end. In drawing out the strip of paper the operator may grasp the same between his 105 thumb and finger within the opening in the frame and drawing the strip out to the desired length may tear it off, the bar 27 serving as a straight edge for the purpose; the frame being entirely open at its under side 110 gives the operator a better hold on the strip and facilitates its being drawn out.

The printing roll 7 is provided at its ends with flanges 28 and 29, the flange 29 being formed with a notch or notches to be engaged by a spring 30 which rides upon the 5 edge of the flange to prevent the roll from being turned backward, the spring also serving the purpose of a bell to notify the operator when the strip has been drawn out the exact length of the ticket, by the clicking noise which it makes in dropping into the notch. The flange 28 is provided with one or more pins 31 to engage a star wheel 32 on the end of a shaft operating a suitable counting device 33 which is mounted in the 10 casing below the opening in the cover 21. If two dies are provided upon the printing roll, two of the pins 31 will be provided on the flange and thus each time a ticket is printed the star wheel will be operated and the exact 15 number of tickets recorded by the counter, such number showing through the opening in the cover of the casing.

Having thus fully described my invention what I claim is:—

25 1. In a device of the character described, a casing having an open top and an opening in one side, the ends of said casing being provided with bearings and slots extending radially toward said bearings, the slots at 30 one side of said bearings opening through the open side of the casing, a cover to close the top of the casing, a printing roll mounted in said bearings, a friction roll having a shaft extending through the slots at one 35 side of said bearings and movable in said slots toward and from said printing roll, an inking roll having a shaft extending through the slots which open through the open side of the casing and movable therein toward 40 and from the printing roll, coiled springs attached at one end to the inking roll shaft and at their opposite ends to the friction roll shaft to normally hold said rolls moved in their slots toward the printing roll, and 45 means at the outer open ends of the slots

for the inking roll for engaging the shaft thereof and holding the same against the action of said springs with the roll projected through the open side of the casing.

2. A device of the character described 50 comprising a casing having an open rear side and a discharge slot for a strip of paper in its front side, the ends of said casing being provided with bearings and slots below said bearings extending vertically toward 55 the same and horizontal radially extending slots opening at their rear ends through the rear edges of said sides, said sides being provided with notches at the rear ends of said slots, a cover for the casing, a printing 60 roll mounted in the bearings in the casing, a friction roll having a shaft with the ends thereof projecting through the vertical slots to guide said roll in its movement toward and from the printing roll, an inking roll 65 having a shaft mounted in the horizontal slots and adapted to be moved therein into engagement with said notches with the inking roll projected through the rear open 70 end of the casing, coiled springs attached at one end of the projecting ends of the shaft of the friction roll and at their opposite ends to the shaft of the inking roll, said springs operating to hold both rolls in yielding contact with the printing roll when the inking 75 roll is in normal position and to hold the inking roll with its shaft in engagement with said notches when the same is moved into engagement therewith, and simultaneously force the friction roll toward the printing 80 roll to grip a strip of paper between them and feed it out through the discharge slot in the front of the casing when said rolls are turned.

In testimony whereof I affix my signature 85 in presence of two witnesses.
